UNITED STATES PATENT OFFICE

ANATOLE DONIS, OF ASTORIA, NEW YORK

DESIGN FOR AN ARTIFICIAL TREE

Application filed October 23, 1929. Serial No. 33,143. Term of patent 3½ years.

To all whom it may concern:

Be it known that I, ANATOLE DONIS, a citizen of Russia, residing at 26-80 Thirtieth Street, Astoria, New York, in the county of Queens and State of New York, have invented a new, original, and ornamental Design for an Artificial Tree, of which the following is a specification, reference being had

to the accompanying drawing, forming part thereof.

The figure is a perspective view of an artificial tree, showing my new design.

I claim:

The ornamental design for an artificial tree as shown.

ANATOLE DONIS.
